Filed Aug. 27, 1973, Ser. No. 392,050

Term of patent 14 years

Int. Cl. D29—02

U.S. Cl. D10—111

FIG. 1 is a front isometric view of a bicycle reflector showing my new design.

FIG. 2 is a rear isometric view of the reflector.

FIG. 3 is a rear isometric view of the reflector with the rear reflective element removed for purposes of disclosure.

FIG. 4 is an isometric view of the rear reflective element, the body of the reflector being omitted for purposes of disclosure.

The cross-hatching which indicates a conventional reflective surface is partially shown in FIGS. 1 through 4 for convenience of illustration, it being understood that the cross-hatching is uniformly continuous over the areas indicated.

I claim:

The ornamental design for a bicycle reflector, substantially as shown and described.
